UNITED STATES PATENT OFFICE.

JOHN F. O'CONNOR, OF CHICAGO, ILLINOIS, ASSIGNOR TO WILLIAM H. MINER, OF CHAZY, NEW YORK.

HIGH-CAPACITY FRICTION DRAFT-RIGGING.

1,278,371.

Specification of Letters Patent. Patented Sept. 10, 1918.

Application filed December 9, 1914. Serial No. 876,216.

To all whom it may concern:

Be it known that I, JOHN F. O'CONNOR, a citizen of the United States, residing at Chicago, in the county of Cook and State 5 of Illinois, have invented a certain new and useful Improvement in High-Capacity Friction Draft-Rigging, of which the following is a full, clear, concise, and exact description, reference being had to the accompanying drawings, forming a part of this specification.

This invention relates to improvements in high capacity friction draft rigging.

An object of the invention is to provide 15 a friction draft rigging for railway cars having a very high capacity and a certain release.

The invention furthermore consists in the improvements in the parts and devices and, 20 in the novel combinations of the parts and devices, as herein shown, described or claimed.

In the drawing forming a part of this specification, Figure 1 is a vertical sectional view of a draft rigging embodying my improvements, parts being shown in side elevation. Fig. 2 is a horizontal sectional view of the structure shown in Fig. 1 and taken on the line 2—2 thereof, the gear being shown 25 under full buff. Figs. 3 and 4 are vertical sectional views taken on the line 3—3 and 30 4—4 respectively of Fig. 1, and Fig. 5 is a detail, broken, sectional view illustrating another form or embodiment of my improvements.

In said drawing, and referring to Figs. 1 to 4 inclusive, 10—10 denote the center sills, to which are attached rear stops 11 and front stops 12, the latter having also limit- 40 ing stops 13. Mounted between the sills is a combined friction cylinder and spring cas- 45 ing A, the front portion 14 of which con- stitutes the friction cylinder and the rear portion 15 the spring casing, the latter hav- ing an integral rear follower 16 formed therewith. Surrounding the member A is a yoke 17 having a hooded end 18 at the front thereof, the side walls of which are provided with elongated slots 19 through which ex- 50 tends a coupler key 20 to connect said yoke with the draw bar 21, the end of the draw bar abutting a front follower 22.

Mounted within the friction cylinder 14, is my improved arrangement of friction de-

vices which, as shown, constitutes a plural- 55 ity of circularly arranged friction shoes 23 having outer cylindrical friction surfaces 24 coacting with the inner cylindrical surfaces 25 of the cylinder; an auxiliary or secondary set of wedges 26 circularly arranged and 60 mounted within the shoes 23, the auxiliary wedges having cylindrical outer surfaces 27 contacting the inner cylindrical surfaces 28 formed on the inner sides of the shoes 23; a main wedge or spreader 29 having inclined 65 wedging faces 30; antifriction rollers 31 mounted between the wedging faces 30 of the main wedge and correspondingly in- clined wedge faces 32 on the inner sides of the auxiliary wedges 26; a block or follower 70 33 interposed between the front follower 22 and the ends of the auxiliary wedges 26; and an auxiliary spring 34 interposed between the inner ends of the auxiliary wedges 26 and inwardly extending flanges 35 on the 75 inner ends of the friction shoes 23. The main wedge 29, as shown, is provided with an integral spring follower 36 between which and the rear wall of the casting A is 80 interposed the main spring consisting of an outer coil 37 and an inner coil 38. The rear wall of the casting A is also provided with an inwardly extending, hollow, perforated 85 boss 39 through which extends a connecting bolt 40, the latter having the head thereof seated in a recess in the block 33, it being understood that the bolt 40 passes through a suitable perforation in the main wedge 29. The bolt 40 maintains the parts in assembled 90 position and the springs under initial compression.

The normal position of the parts is as shown in Fig. 1, wherein the front follower 22 is spaced a short distance, say half an inch, from the outer ends of the friction shoes 23. The block 33 is interposed be- 95 tween the follower 22 and the auxiliary wedges 26, which latter are pressed for- wardly under the action of the springs 34, 37 and 38. Upon inward movement of the 100 draw bar, the front follower presses the block 33 inwardly, which in turn moves the auxiliary wedges 26 inwardly and com- presses the springs 34, 37 and 38 during 105 which movement, the friction shoes will remain immovable on account of the frictional resistance between the outer surfaces thereof and the friction surfaces of the cyl-

inder. After the front follower 22, block 33 and wedges 26 have been moved inwardly to such a point that the front follower contacts with the outer ends of the friction 5 shoes 23, then the block 33, auxiliary wedges 26 and shoes 23 all move inwardly without relative movement and the frictional resistance is increased by the main wedge which is resisted by the main spring and which 10 acts through the antifriction rollers, auxiliary wedges and friction shoes to force the latter into greater frictional contact with the inner surface of the friction cylinder 14, this movement being continued until the 15 front follower is stopped by engagement with the limiting stops 13 and the front end of the casting A.

Under release, the auxiliary wedges 26 will first be forced outwardly by the springs 20 34, 37 and 38, the friction shoes remaining stationary during the initial portions of the release. After the auxiliary wedges 26 and main wedge 29 have moved outwardly to such an extent that the follower 36 engages 25 the inner ends of the friction shoes, the latter will then begin to move outwardly, which movement continues until the parts assume their full release position. Under draft, it will be understood that the same sequence 30 of actions takes place, except that the casting A is the part which moves and the block 33 and front follower 22 are held stationary.

In the form shown in Fig. 5, a casting A is 35 provided, similar to that shown in the first four figures, also a set of friction shoes 23, a set of auxiliary wedges 26, auxiliary spring 34 and antifriction rollers 31. A main wedge 129 is provided, similar to the wedge 40 29, except that the spring follower 136 is made separate from the wedge. In place of the block 33 shown in Figs. 1 to 4, a block 133 is provided, which has an outer flange 134 and which, when the front follower 22 45 is moved slightly inwardly, engages the outer ends of the shoes 23 instead of the latter being directly engaged by the front follower. The operation is similar to that above described for the construction shown 50 in Figs. 1 to 4.

From the preceding description, it will be apparent that the device which I have designed provides for an exceedingly high frictional resistance and one in which the 55 angle of thrust from the wedge to the shoes and thus to the friction cylinder may be varied as desired, the load on the main wedge always being limited to the pressure of the main springs.

60 Although I have herein shown and described what I now consider the preferred embodiment of my invention, it will be understood that changes and modifications may be made in the details and arrangements of parts, such for instance as the omis-

sion of the spring 34. Therefore, I do not wish to be limited to the structure herein described in detail, but contemplate all changes and modification that come within the scope of the claims appended hereto. 70

I claim:

1. In a draft rigging for railway cars, a friction gear comprising a friction shell, a main wedge, a spring, friction shoes having friction surfaces on the exterior thereof 75 coöperating with the friction surfaces of said shell, said friction shoes having also interior wedge engaging surfaces, and a set of auxiliary wedges having outer bearing surfaces coöperable with the said inner surfaces of the friction shoes, said main wedge acting directly against said spring.

2. In a draft rigging for railway cars, a friction gear comprising a friction shell, a main spring, a main wedge, auxiliary 85 wedges, and friction shoes, the friction shoes acting directly against the friction shell and the auxiliary wedges against the friction shoes, the latter remaining stationary relative to the shell during initial action of buff and draft, and an auxiliary spring interposed between the friction shoes and the auxiliary wedges.

3. In a draft rigging for railway cars, a friction gear comprising a friction shell, a 95 main wedge, a main spring, a set of friction shoes coöperable with said shell, a set of auxiliary wedges interposed between the main wedge and the friction shoes, said friction shoes remaining stationary relative to 100 the shell during initial action of buff and draft, a follower, and means for transmitting pressure from said follower first directly to the auxiliary set of wedges and finally to said wedges and the friction shoes 105 simultaneously.

4. In a draft rigging for railway cars, the combination with a follower, of a movable friction shell, friction shoes coöperable with said shell and having their front ends extended outside of the shell but normally spaced from said follower, a spring within said shell, wedge acting means interposed between said shoes and said spring, said means comprising main and auxiliary 115 wedges, an auxiliary spring interposed between the auxiliary wedges and the friction shoes, and means interposed between the follower and the auxiliary wedges for transmitting the pressure to the latter prior to the pressure being transmitted to the friction shoes. 120

5. In a friction draft gear, the combination with a friction shell, of a plurality of annularly arranged friction shoes coöperable with said shell, a set of annularly arranged auxiliary wedges coöperable with said shoes, a main wedge and spring means resisting movement of said shoes and wedges, said auxiliary wedges being movable longi- 125

tudinally of the shell and relatively to the friction shoes during initial portions of buffering movement.

6. In a friction draft gear, the combination with a friction shell, of a plurality of friction shoes slideable longitudinally thereof, a main spring, a main wedge directly engaging said spring, a plurality of auxiliary wedges interposed between said main wedge and said shoes, anti-friction rollers interposed between said main and auxiliary wedges, and means engaging said auxiliary wedges for actuating the latter independently of the shoes during initial portions of 10 the actuation of the gear.

7. In a shock absorbing mechanism of the character described, the combination with a combined friction shell and spring casing, of a plurality of friction shoes within the 20 friction shell and coacting with the interior

surface of the latter, said friction shoes being normally extended partly beyond the end of the friction shell, a series of auxiliary wedges within and coacting with the friction shoes, the number of auxiliary 25 wedges corresponding to the number of friction shoes, a main wedge coacting with the auxiliary wedges, spring means directly resisting movement of the main wedge, and means for transmitting pressure primarily 30 to the auxiliary wedges prior to application of pressure to the friction shoes whereby the auxiliary wedges have a preliminary movement relatively to the friction shoes and thereafter the auxiliary wedges and 35 friction shoes are moved simultaneously.

JOHN F. O'CONNOR.
